The ornamental design for an indicator disc, as shown and described.

DESCRIPTION

The patent or application file contains a least one drawing executed in color. Copies of this patent or patent application publication with color drawing(s) will be provided by the Office upon request and payment of the necessary fee.

FIG. 1 is a plan view of an indicator disc showing my new design; and,

FIG. 2 is an opposite side plan view thereof.

The dashed broken lines define the bounds of the claimed design and form no part thereof.

The front, rear, left, and right sides of the article are not shown in the drawings or described in the specification. It is understood that the appearance of any part of the article not shown in the drawings or described in the specification forms no part of the claimed design.
